(57) **CLAIM**

The ornamental design for a user interface for a television display screen, as shown and described.

DESCRIPTION

FIG. 1 is a front view of a user interface on a television display screen showing our new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof; and, FIG. 6 is a front view of a sixth embodiment thereof.

The broken line drawing of a television display screen in all views is for illustrative purposes only and forms no part of the claimed design.
